DOOR ESCUTCHEON PLATE

Bruno H. Schindler, Inglewood, Calif., assignor to The Peabody Company, Inc., Los Angeles, Calif., a corporation of California

Application July 5, 1955, Serial No. 36,805

Term of patent 14 years

(Cl. D50—6)

FIG. 1.

FIG. 2.

FIG. 3.

FIG. 4.

Fig. 1 is a front elevational view of a door escutcheon plate, showing my new design.

Fig. 2 is a top plan view of the plate,

Fig. 3 is a section on line 3—3 of Fig. 1, and

Fig. 4 is a fragmentary section on line 4—4 of Fig. 1.

I claim:

The ornamental design for a door escutcheon plate, as shown.
